UNITED STATES PATENT OFFICE.

ERLE G. ASHLEY, OF MEMPHIS, TENNESSEE. ASSIGNOR OF ONE-THIRD TO HARRY B. ANDERSON AND ONE-THIRD TO DWIGHT R. THOMAS. BOTH OF MEMPHIS, TENNESSEE.

WOODWORKING MACHINERY.

Application filed August 31, 1921. Serial No. 497,256.

To all whom it may concern:

Be it known that I, ERLE G. ASHLEY, a citizen of the United States, residing at Memphis, in the county of Shelby and State 5 of Tennessee, have invented certain new and useful Improvements in Woodworking Machinery, of which the following is a specification.

My said invention relates to an improvement in woodworking machinery in which a plurality of blocks of wood may be operated on simultaneously and each block or board as it passes through the machine may have its edges evened, its sides planed and 15 grooved and finally be sawed apart to form strips such as are used for battery separators. It will be understood that the number and kind of operations may be varied by making obvious changes in the machine.

Referring to the accompanying drawings which are made a part hereof and on which similar reference characters indicate similar parts,

Figure 1 shows a plan of my improved 25 machine,

Figure 2 an end view thereof, and

Figure 3 a detail of the driving gearing.

In the drawings reference character 10 indicates a frame for supporting various 30 parts of the machine. In a lateral extension of the frame is journaled a shaft supporting at its ends two circular saws 11 and 12. The shaft as here shown is driven by a motor 13. The upper part of the frame 35 is provided with a set of guide and driving rollers 17 arranged in pairs at each end. Each set of rollers serves to guide a board or a strip of lumber 18 toward the corresponding saw. The rollers are held in close 40 engagement with the board by means of springs 19 provided with adjusting screws 20 for varying their tension.

At each side of each board there is a revolving head 21 and each head may be provided with knives for planing and corrugating the adjacent face of the board and 45 with horizontal knives for trimming the upper and lower edges as described in co-pending application No. 497,255 of even date herewith.

Each revolving head is provided with a guard 22, the guard extending around the head and forward and rearward over the rollers and acting as a housing and bearing support for the rollers. The guards 55

also extend forward adjacent the saws and serve to some extent as guards therefor, at the same time serving effectively to guide the boards to the corresponding saws and preventing bending or sidewise movement 60 of the boards. Directly opposite the later acting head of each set is a plate 23 carried by the corresponding guide and adjustable toward the board by set screws 24 to prevent the board from bending away from the opposed head whereby it might fail to be properly trimmed.

I have shown the front set of rolls connected to a common driving shaft 25 and the rear set to a common driving shaft 26, 70 the shafts being driven by a common chain 27 passing over sprocket gears thereon and a chain 28 in turn connected to the rear shaft and to a motor 29 for driving the latter. The shaft 25 has at each end a 75 pair of beveled gears 30 and 31 engaging corresponding gears on the rollers 17 and the shaft 26 is similarly connected to the rear pair of rollers. The bevel gears on shafts 25 and 26 are splined to the shafts 80 and movable endwise thereof to permit adjustment of rollers 17. Each rotary head is preferably driven by a separate motor as shown at 32 and 33.

It will be obvious to those skilled in the 85 art that my machine may be modified in various ways without departing from the spirit of the invention or the scope of the appended claims.

Having thus fully described my said invention, what I claim as new and desire to secure by Letters Patent, is:

1. In a woodworking machine, a plurality of cutterheads arranged in opposed pairs, individual driving means for the cutterheads, a plurality of spring-pressed feed rollers for feeding a strip of wood to each cutter-head, a saw in advance of each pair of cutter-heads and lying in a plane passing between them, a plurality of spring-pressed feed rollers acting on each strip between the cutter-heads and the saw, and common driving means for all said feed rollers, substantially as set forth.

2. In a machine for making battery separators, a pair of opposed rotary cutterheads arranged with one in advance of the other and carrying grooving and planing means, a pair of feed rollers in front of each cutter-head, a guard for each cutter- 105 110

head comprising parts resting against the work and transversely slotted end extensions, bearings for the feed rollers movably supported in the slots, and springs acting on said bearings to force the feed rollers toward the work, substantially as set forth.

3. In a machine for making battery separators, a pair of opposed rotary cutter-heads arranged with one in advance of the other and carrying grooving and planing means, a pair of feed rollers in front of each cutter head, a guard for each cutter-head comprising parts resting against the work and transversely slotted end extensions, bearings for the feed rollers movably supported in the slots, springs acting on said bearings to force the feed rollers toward the work, one of said guards having a recess, a plate in the recess directly opposed to a cutter head, and a plurality of spaced-apart set screws for adjusting said plate, substantially as set forth.

4. In a machine for making battery separators, a pair of opposed rotary cutter-

heads arranged with one in advance of the other and carrying grooving and planing means, a pair of feed rollers in front of each cutter-head, a guard for each cutter-head comprising parts resting against the work and transversely slotted end extensions, bearings for the feed rollers movably supported in the slots, springs acting on said bearings to force the feed rollers toward the work, a saw in advance of the forward pair of rollers located in a plane passing midway between them and extensions on said guard curved at their forward ends to lie closely adjacent to and concentric with the saw, substantially as set forth.
